Primary Examiner — Philip S Hyder(74) *Attorney, Agent, or Firm* — FisherBroyles, LLP(57) **CLAIM**

The ornamental design for a wedge, as shown and described.

DESCRIPTION

FIG. 1 is a top-front-left perspective view of the wedge; FIG. 2 is a bottom-front-left perspective view thereof; FIG. 3 is a top-front-right perspective view thereof; FIG. 4 is a bottom-front-right perspective view thereof; FIG. 5 is a top-rear-left perspective view thereof; FIG. 6 is a bottom-rear-left perspective view thereof; FIG. 7 is a top-rear-right perspective view thereof; FIG. 8 is a bottom-rear-right perspective view thereof; FIG. 9 is a front elevation view thereof; FIG. 10 is a rear elevation view thereof; FIG. 11 is a left side elevation view thereof; FIG. 12 is a right side elevation view thereof; FIG. 13 is a top plan view thereof; FIG. 14 is a bottom plan view thereof.

FIG. 15 is a cross-section view taken along line 15-15 of FIG. 5; and, FIG. 16 is a partial cross-section view showing section 16 of FIG. 15.

The dashed lines in the drawings represent portions of the wedge that form no part of the claimed design.

1 Claim, 13 Drawing Sheets(56)
